UNITED STATES PATENT OFFICE.

JOSEPH KAUFMAN, OF BRONXVILLE, NEW YORK, ASSIGNOR TO AMERICAN SAFETY RAZOR CORPORATION, OF NEW YORK, N. Y., A CORPORATION OF VIRGINIA.

CONTAINER.

Application filed January 29, 1925. Serial No. 5,491.

My invention relates generally to containers and more particularly to containers for shaving apparatus.

Various types of safety razors are made of 5 separable parts with the handle member separate from the blade holding member. A container for such types of razor should preferably make provision for receiving conveniently the parts of the razor when dis- 10 assembled for shipment and furthermore, should have some provision for receiving and holding the razor assembled, and also for receiving new blades separate from the old or discarded blades.

15 One of the objects of my invention is a container in which by a simple, inexpensive and efficient construction, provision is made for holding the various parts of the razor either assembled or disassembled and the 20 new blades separated from the old or discarded blades.

Razors of the safety type have come into almost universal use, having reached the stage where they might be termed a household utility, used almost daily. It is a practice to-day among users of safety razors to deposit the container in any convenient place, such as a medicine chest along with all other medicinal, household or toilet accessories found generally in the home, and when such user desires to shave, he removes the container from the medicine chest or wherever else the container may have been placed, opens the container, removes the shaving apparatus therefrom, places the container in whatever temporary place he finds convenient, finishes the shaving operation, replaces the razor in the container, closes the container and replaces it in the medicine chest. Not only does the use of the implement entail all this, but there is no assurance that when the razor container is replaced in the medicine chest that it will be found where it was originally put, even when the user keeps it always in one definite place, which is frequently not the case; furthermore, it is the experience of most users that it is necessary to shift a great deal of the articles or accessories contained in the medicine chest to reach the container.

Another object of my invention, therefore, is the provision whereby the container is of such a type that it can be given a fixed

association or position at all times in the 55 bath room or anywhere else where it may be desired to keep the container.

Another object of my invention is the provision of a container in which the container can remain in fixed position and in which the 60 shaving apparatus can be removed therefrom and inserted therein without shifting or handling of the container.

Furthermore, it is frequently the habit of the user even when he replaces the parts and 65 accessories in the container and places the container in the medicine chest, to leave the discarded or old blades lying around, which not only is a source of annoyance to those who are supposed to clean and tidy up the 70 bath room, but also a frequent source of discomfort because of the fact that the handling of the safty razor blades by one not accustomed thereto is hazardous. One of the reasons that gives rise to this neg- 75 ligence of the user in letting his discarded blades lie around is the fact that he finds it easier to leave the used blade where it is than to replace it in the container.

Another object of my invention, therefore, 80 is the provision of a container which not only makes provision for receiving the discarded and used blades, but which is of such a character and is so positioned in the bath room or elsewhere, that the user not only finds it just 85 as easy to place it in the compartment provided therefor, as to leave it on the wash bowl, but its location is such that the shaver is made constantly aware of the presence of the convenient means for receiving the discarded blades.

Another object of my invention is the provision of a container for a safety razor of 90 such a character that the container can serve as a shipping package with the parts disassembled and held therein and can alternatively serve as a receptacle with the parts of the razor assembled.

Another object of my invention is the provision of a container so arranged and constructed that the razor parts and accessories received therein can be readily and easily withdrawn and replaced and more particularly a container in which there is provided a compartment which is so dimensioned and 100 constructed with reference to the handle, that the handle can be received therein only 105 on end, with that end of the handle extend-

ing above the compartment to which the blade holder is to be attached, whereby the blade holder can be disassembled from the handle for shipment and received therein 5 assembled therewith ready for use.

Another object of my invention is the provision of a container of the type referred to in which a closure member is employed which is separable from the container, so that if 10 desired the closure member can be removed from the container permanently or only temporarily during the shaving operation, so that free and easy access for the insertion and removal of the shaving apparatus can be had.

Another object of my invention is the provision of a closure member which is so constructed and associated with the container that it is fixedly held in position by the 20 inherent resiliency of the parts and in which it can be removed from said closure position merely by a flexing of the parts and furthermore, such a construction and association of the parts as to prevent the cover from being moved beyond its predetermined position of closure.

My invention generally includes the provision of a new, simple, inexpensive and convenient container for a shaving apparatus in 30 which the apparatus can be received in disassembled form with the old or discarded blades separated from the new blades and in which provision has been made whereby such container can be given a permanent position 35 without interfering with the free access thereto and in which the closure member is so associated with the container that it can be completely removed therefrom without difficulty and at will.

My invention further includes the construction of a container made up of a plurality of compartments, preferably arranged side by side for containing the parts of the razor and the accessories, from metal stampings and also includes the manner of assembling the blanks whereby a durable assembly is attained.

For the attainment of these objects and such other objects as may hereinafter appear or be pointed out, I have illustrated in 50 the drawing, one embodiment of my invention wherein—

Fig. 1 is a perspective view of my container, arranged to be fixed to any part of the bath room, or any other part of the house, and with the shaving apparatus therein and with the closure in position;

Fig. 2 is a view similar to Fig. 1 showing the closure member completely removed 60 from the container;

Fig. 3 is a view similar to Fig. 1 without the closure member and with the shaving apparatus completely assembled, but in position in the container;

Fig. 4 is a section taken on line 4—4 of

Fig. 3 with the shaving apparatus removed;

Fig. 5 is a section taken on line 5—5 of Fig. 1 with the container empty;

Figs. 6, 7, 8 and 9 are elevational views of the blanks which, when assembled, form 70 the container of Fig. 1.

Upon viewing Figs. 2 and 4 of the drawing, it will be observed that the container is so made as to provide the compartments 10 and 11 which are preferably, although not necessarily, substantial duplicates, but arranged reversely and the smaller tubular compartment 12 positioned therebetween. The tubular compartment 12 is preferably of a diameter and of a depth so as to receive 80 conveniently therewithin the cylindrical portion of the handle of a well known type of razor with the narrowed neck portion of said handle member projecting thereabove.

Where it is desired to keep the discarded blades separate from the new blades, one of the compartments as that numbered 10 may serve to receive one group and the other compartment 11 can be used to receive the other group, and the razor handle can be positioned in the tubular compartment 12 with the blade holding portion thereof assembled therewith, as shown in Fig. 3 of the drawing. On the other hand, where it is desired to keep the blade holding part of the razor separate from the handle member, one of the compartments 10 or 11 may be used for receiving the blade holding part of the handle and the other compartment to receive the new blades alone, other provisions being made for the old blades; or both the new and the old blades where it is so desired can be received in either of the compartments 10 or 11.

In my preferred manner of making the 105 container of Fig. 1, I employ the blanks shown in Figs. 6, 7, 8 and 9 of the drawing which may be in the form of sheet metal stampings which I will now describe more fully.

In Fig. 6 of the drawing, I show the blank 15 comprising the section 16 to form the rear wall of the container and the section 17 to form the bottom thereof. The rear wall is provided with ridges or ribs 18, 19, 20 and 21, stamped inwardly therefrom, either simultaneously with the stamping of the blank or thereafter and the purposes of which will be pointed out shortly. The bottom of the blank is provided with the curved side flanges 22 and 23 shaped to conform to the shape which it is desired to give to the side walls. The blank 15 is further provided with the flanges 24, 25, 26 and 27, the purposes of which will be more fully pointed out in connection with the assembly of the container.

In Fig. 7 of the drawing, I show the blank 30 from which is to be formed the front and side walls of the container, the front and

side walls being made up as shown in Fig. 2 of the intermediate sections 31, the portions 32 and 33 extending angularly therefrom and in substantial parallelism, from which portions 32 and 33 extend the portions 34 and 35 which form the front walls of the container and which are preferably positioned in the same plane and from which front walls in turn extend the side walls 36 and 37.

These front and side walls of the container just described are formed from the blank of Fig. 7 by bending this blank along vertical lines 40, 41, 42, 43, 44 and 45. The portions of the blank between these lines of bend, form the parts of the front and side walls already described, in an obvious manner.

The side walls 36 and 37 are preferably given the shape shown in Figs. 1, 2, 3 and 4 by bending the portions of the blank which form these side walls along the lines 46, 47, 48 and 49 so as to provide the portions 50 and 51 in each side wall which are in substantially the same plane and substantially at right angles to the front walls and curving the portions of the blank in between the lines of bend 46 and 48 on one side and 47 and 49 on the other so as to provide the curvature at the side of that wall as shown at 52 in Fig. 2. The blank 30 is further provided with the side flanges 54 and 55 and with the bottom flanges 56 and 57.

The blank 15 of Fig. 6 and the blank 30 of Fig. 7 bent and shaped as described are assembled in the following manner: The bent and shaped blank of Fig. 7 is positioned upon the portion 17 of the blank 15 which is to form the bottom of the container, and in full registry therewith, that is with the curved portion 52 of the side walls of the blanks 30 in registry with the curved portion of the parts 22 and 23 of the bottom member of the blank 15 of Fig. 6 and with the flanges 56 and 57 of the blank 30 of Fig. 7 in registry with the flanges 26 and 27 of the blank 15 of Fig. 6, and with the two blanks so assembled, the dimensions are so predetermined that the wall 31 of the blank 30 will abut against the wall 16 of the blank 15 (see Fig. 2).

The flanges 56 and 57 of the blank 30 are now bent as shown in Fig. 5 and the flanges 26 and 27 of the blank 15 rolled or beaded thereabout as shown in Figs. 1, 2 and 3 of the drawing. The end flanges 54 and 55 are bent outwardly and oppositely with reference to the blank 30 and the flanges 24 and 25 of the blank 15 are now rolled or beaded about these bent flanges 54 and 55 and it will be found that by the interlocking of these flanges at the sides and at the bottom of the two blanks of Figs. 6 and 7 bent in shape as shown and assembled as desired, form a relatively rigid and secure

container structure, providing the compartments 10 and 11 already described.

In order to still further secure these two blanks in fixed relationship and association, I cut out from the blank 30 preferably before it is bent and shaped as described, the lips 60 and 61 (see Fig. 7) formed by the parallel horizontal cuts 62 and 63 and the vertical cuts 64. These lips 60 and 61 are then passed through the opening 66 formed in the rear wall 16 of the blank 15 of Fig. 6 (see Figs. 4 and 6) and then bent around the edges of this slot as shown in Fig. 4. The vertical ribs 20 and 21 already described as formed in the blank 15 of Fig. 6, it will be observed, upon viewing this figure as well as Fig. 4, are formed adjacent the interlock between the flanges 24 and 25 of the blank 15 and the corresponding flanges 54 and 55 of the blank 30, and will not only give rigidity to the structure, but form an abutment so as to prevent the release of the interlock and the separation of the members.

The container formed, as described and illustrated in the various figures, provides a space between the walls 31, 32 and 33 and this space I utilize as follows: In Fig. 8 of the drawing, I show a blank 70 provided with the pairs of ears 71 and 72 extending from the opposite sides thereof, and with the lips 73 stamped therefrom intermediate the sides thereof. The blank 70 is so dimensioned that when bent into tubular form and circular in cross-section, it will be conveniently received within the space between the walls 31, 32 and 33 referred to, and will be of a height substantially equal to the height of the said walls and is intended to be so positioned as to bring the oppositely extending lips 71 and 72 in registry with the opening 74 formed in the blank 30 (see Fig. 7) through which these two sets of lips can be passed and bent oppositely as shown in Fig. 4.

The blank 30 is further provided with the slits or openings 75 arranged to register with the lips 73 formed in the blank 70 of Fig. 8 and which lips can be passed through such openings and bent about the sides thereof as shown in Fig. 4, and in this manner, the tubular compartment formed from the blank 70 as described, is securely and fixedly anchored to the main container sections.

Upon viewing Fig. 1 of the drawing, it will be observed that the portion 16 of the blank of Fig. 6 which is to form the rear wall of the container is higher than the rest of the container so as to provide the extension 81 in which extension is formed the opening or hole 81, whereby the container with its contents can be maintained in fixed position as by a nail, wherever desired, as on the side of the medicine chest.

This rear wall of the container is further provided with the key hole slot 66 already referred to (see Fig. 6) so that where desired, this also may be used as a method of 5 attachment.

In the use of a container constructed in accordance with my invention and particularly in the use of the embodiments illustrated in the drawings, the handle member 10 of the razor is received in the compartment 12 formed from the blank 70 and anchored to the rest of the structure in the manner already described and that the blade holding part of the razor may be attached there- 15 to as in Fig. 3 or separated therefrom as in Fig. 2 and in the latter arrangement, this blade holding part of the razor will be received in one of the compartments 10 or 11 and the other compartment arranged to 20 receive either the new blades alone and other provision made for the old and discarded ones or both the new and discarded blades. In order to permit the user to readily take hold of and remove blades or parts of the 25 razor from the compartments 10 and 11, the walls 34 and 35 are cut away at their upper edges as shown at 34' and 35'.

In Fig. 9 of the drawing, I show the blank from which a type of closure is formed 30 which can be so associated with the container already described, that it will on the one hand serve to completely and effectively seal the compartments within which the parts of the razor are held, and yet can 35 permit of quick and complete removal therefrom so as to permit free access to the contents of the compartments and this blank 80 (see Fig. 9) is shaped so as to conform more or less to the cross-section through the 40 compartments as shown in Fig. 4, except that it is provided with the lips 81 and 82 which are bent downwardly as to form a closure for the cut away portions 34' and 35'.

Closure member 80 is provided with trans- 45 verse ribs 83, 84 and 85 so as to give rigidity thereto and is further cut away at 86 so as to permit of the positioning of the cover without interfering with the projecting part 50 of the handle member of the razor received in the compartment 12 and this cut away portion is preferably so arranged and constructed that it will be positioned closely adjacent to the narrowed neck of this handle member projecting above the compartment 55 12 so that in this way, this handle member will be prevented from falling out in case the receptacle is upset.

To place this cover member 80 in its compartment sealing position, the inner edge 60 87 thereof (see Fig. 2) is positioned completely below the ribs 18 and 19 of the back member 16 (see Fig. 1) and the downwardly bent lips 81 and 82 are then positioned inwardly of the walls 34 and 35 and within

the compartments 11 and 12 and the parts are so arranged that to do this, the metal of the cover must be sprung due to the engagement of its rear edge 87 beneath the ribs 18 and 19 and the engagement of the lips 81 and 82 with the inner faces of the walls 34 and 35. As a result of this arrangement, the cover member is held in its position of Fig. 1 and the cover must be flexed slightly so as to permit the edge 87 thereof to pass the ribs 18 and 19. I thus attain 70 an efficient method of holding the cover in its closed position.

From the description thus far given, it will be understood that I have devised a container which not only serves its purposes for holding the different parts of the safety razor, but also can be secured fixedly in any pre-determined place and that the use of the razor does not require the handling of the container at all. Furthermore, by the character of the cover, I employ and the manner of its association with the container, I not only arrange for a proper sealing of the compartments, but also allow for quick removal of the cover and free access to the 90 contents of the compartments.

From the description of my invention, it will be understood that I have devised a construction which serves its functions not only from the aspects of a razor container generally, but also from the aspects of a shipping packet as well as a display device. As shown in Fig. 1, it serves efficiently as a shipping packet as well as a razor container and as illustrated in Fig. 3, it serves 100 equally well as a display device, and with the cover in position, it serves its full functions whether the blade holding part of the razor is attached as in Fig. 3 or detached as in Fig. 2. This results from the fact that by positioning the razor handle in the compartment 12 on end, the compartment is of less height than the handle so that that part of the handle which serves to secure the blade holder thereto extends above the 110 compartment 12.

The cover member 80 may be made of sheet metal. I have found however that by making it of a transparent material such as celluloid, it not only has all the attributes 115 of sheet metal, at least so far as relative rigidity and flexibility are concerned, but in addition, it exposes to view the contents of the compartments.

One method of assembling the blanks to 120 make the container on a quantity production basis is to first bend the flanges 24, 25, 26, and 27 into the beads as shown in Fig. 2 of the drawing before the parts are assembled and to give to the flanges 54, 55, 56 and 57 the conformation which they have in the completed article, and then assemble these two blanks so formed and bent as al-

ready described, as follows, it being understood that the ribs 20 and 21 have already been formed in the blank 15 of Fig. 6:

I position the stated blank 30 above the shaped blank of Fig. 6 with the flanges 54 and 55 in registry with the channel in the beads 24 and 25, and then slide the flanges 54 and 55 downwardly along this channel, so that these flanges are engaged between the beads 24 and 25 and the ribs 20 and 21 until the blank 30 is fully inserted. I then snap the flanges 56 and 57 (see Fig. 7) within the channel in the beads 26 and 27 so that the parts are fully engaged. I then pass the lips 60 and 61 through the openings 66 and bend them back as shown in Fig. 4. The blank 70 can be attached to the parts to which it is to be affixed either before this final assembly or after the assembly as desired.

Having thus described my invention and illustrated its use, what I claim as new and desire to secure by Letters Patent is—

1. A safety razor container comprising a plurality of compartments, adjacent walls being formed to provide a depression therebetween, and another compartment adapted to be supported in said depression exteriorly of the first mentioned compartments with its walls contacting with the walls aforesaid, and means for interconnecting said walls.

2. A safety razor container comprising a plurality of compartments arranged adjacent each other, one of the compartments being arranged to receive the handle member of the razor and a sealing cover member therefor for sealing the compartments so contoured as to expose sufficient of the handle receiving compartment so as to permit of the portion of the razor to be exposed thereabove.

3. A safety razor container comprising a plurality of compartments arranged adjacent each other, one of the compartments being arranged to receive the handle member of the razor and a sealing cover member therefor for sealing the compartments so contoured as to expose sufficient of the handle receiving compartment so as to permit of the portion of the razor to be exposed thereabove, said cover member, however, being arranged to prevent the removal of the handle member.

4. A packaging device for safety razors and accessories comprising a plurality of compartments and a cover member therefor, the parts being so arranged and constructed as to seal the accessories in the compartment and lock the razor therein with the blade holding portion of the razor handle exposed.

5. A safety razor container comprising a plurality of compartments arranged adjacent each other, one of the compartments being arranged to receive the handle member of the razor and a transparent sealing cover member therefor for sealing the compartments so contoured as to expose sufficient of the handle receiving compartment so as to permit of the portion of the razor to be exposed thereabove. 65

6. A safety razor container comprising a plurality of spaced compartments capable of receiving razor accessories, razor parts, and a handle member thereof, a sealing cover arranged to prevent displacement of the handle and parts mentioned, while permitting a portion to protrude therethrough, said cover having means making frictional contact with walls of compartments and 80 means on the walls to prevent displacement of the cover. 75

7. A safety razor container comprising a plurality of spaced compartments capable of receiving razor accessories, razor parts, and a handle member thereof, a sealing cover arranged to prevent displacement of the handle and parts mentioned, while permitting a portion to protrude therethrough, said cover having means making frictional contact with the inner portions of walls of compartments and means on the walls to prevent displacement of the cover, said cover being formed to fit within some compartments while spanning the handle holding 90 compartment. 95

8. A safety razor container made of sheet metal, and assembled from one single sheet forming the back walls and bottom and another single sheet defining a plurality of 100 spaced compartments and a spacer member having walls defining means capable of holding a razor handle holding compartment, channels and beads formed on said first mentioned sheet and tongues formed 105 on said second sheet to form engagement between said back walls and compartment defining sheet.

9. A sheet metal safety razor container providing a plurality of compartments 110 with a space therebetween, one single sheet forming the bottom and back walls thereof and another single sheet forming the side walls and front, a razor handle holding compartment positioned in the afore-mentioned space, and means for interconnecting said sheets to each other and said second named sheet to said razor handle holding compartment. 115

In witness whereof, I have hereunto signed 120 my name.

JOSEPH KAUFMAN.
